FURNACE WALL

Frank Burr Bigelow, Detroit, Mich., assignor to
 Bigelow-Liptak Corporation, Detroit, Mich., a
 corporation of Michigan

Application May 29, 1939, Serial No. 276,351

10 Claims. (Cl. 72—101)

The current invention pertains to certain structural features of advantage and benefit in furnace-wall constructions of the suspended type and it concerns more particularly the method or means of support for the bricks or refractories which will effect a permanent furnace enclosure with suitable provision for the expansion and contraction of the refractory elements.

Another object of the invention is to provide a design of supports which allows a minimum amount of surface of the sustaining members to be exposed to the cooling effect of the lower temperature at the outside of the furnace-lining and which effects a material reduction in heat-release therefrom and in substantial lessening in conduction and radiation losses heretofore met with in structures of this character.

In the past, it has been customary in suspended furnace-walls to provide metallic supporting-members of a style and form with a substantial surface exposed and subjected to the cooling effects outside of the furnace, or in the air-lanes, in order to prevent an excessive and detrimental heating of these members under certain operating conditions.

Modern designs of boilers, oil process and other types of heaters are much more efficient and hence small losses at these higher efficiencies are more serious than those occurring in structures operating at lower efficiencies.

These losses are of three principal kinds: (a) those due to heat conduction through the walls of the furnaces and convection areas, (b) those occurring by reason of air-infiltration through the setting and which tend, especially in convection areas to increase weights of the products of combustion and dilute the combustion gases, especially the carbon-dioxide, and (c) losses occasioned by exfiltration of furnace-gases in so-called high-head or high-draft boilers or similar heat-appliances which are not only direct losses in themselves, but which also have deleterious effects upon other parts of the furnace-structure.

This signifies that the supporting-members of such constructions will be embedded within the refractory blocks or the insulation, or both, resulting thereby in increased temperatures of the supporting-members to the point where some type of alloy or heat-resisting metals must be used. This means the employment of higher cost materials, which in turn, necessitate that the size and weight of the supporting-members be kept at a minimum.

Other advantages of the new, improved construction will become apparent to those skilled

in the art from a consideration of a present preferred embodiment of the invention illustrated in detail in the accompanying drawings forming a part of the specification.

In these drawings, in which like reference characters for simplicity have been employed to designate the same parts throughout the views—

Figure 1 is a fragmentary isometric section through one style of wall;

Figure 2 is a fractional view of such wall as 10 seen from the front or inside of the furnace;

Figure 3 is a sectional portion of the wall as viewed from the outside;

Figure 4 is a fragmentary, vertical section disclosing another method of anchoring the tiles; 15

Figure 5 is a horizontal section on line 5—5 of Figure 2;

Figure 6 presents a modified means for supporting the brackets;

Figures 7, 8, 9, 10, 11 and 12 illustrate different 20 shapes of refractory bricks or tiles and a locking-key;

Figure 13 is a partial isometric section through a different form of wall;

Figure 14 is an incomplete view of such wall, 25 as seen from the inside of the furnace with parts cut away to show the supporting members;

Figure 15 is a horizontal section on line 15—15 of Figure 14;

Figure 16 is a vertical section on line 16—16 30 of Figure 15;

Figures 17 and 18 are perspective views of refractory tiles; and

Figure 19 is an alternate or plate-panel construction for carrying the brackets.

Referring to these drawings, it will be noted that the furnace-wall, as represented more especially in Figures 1, 2, 3 and 5 comprises a series of upright, spaced-apart metal members or columns 21, 21 to which metal brackets 22, 22 40 are attached by bolts, rivets, or other suitable means as, for example, is indicated in Figure 6, wherein a double-ended notched or recessed bracket 22 is mounted on the vertical, supporting element 21 by means of a socket-member 120 45 fastened to the part 21 and fitted around and supporting the middle portion of the bracket, all as is fully illustrated.

These wall-brackets 22, 22 in turn carry horizontal pipes, rods or such other form of horizontal members 23, 23 as may be desired with the end portions of the pipes or other members accommodated in apertures extended through the outstanding arms of the brackets.

If pipes are employed, provision can be made 55

for the circulation of air, gas or liquids through the same to provide for the cooling of their supporting members as shown by the arrows in Figure 1 and means may also be used for reclaiming the heat from the same, if it is so desired. In employing the pipes in this relation, they may be connected in series, or in parallel, or both methods may be used more or less conjointly.

10 The refractory members or tiles are of special shapes to accommodate this particular type of support and these blocks or bricks are carried and held in place by the vertically-spaced pipes 23 or equivalent members, and, in the construction 15 illustrated herein, these tiles are arranged in groups of two shapes, 24 and 25, and when assembled they are held firmly in position, and, at the same time, provision is made for the expansion of the individual tiles without incurring 20 pressure upon adjoining tiles by means of an expansion-joint 26, at suitable intervals.

The members comprising this wall are assembled by securing the brackets 22, 22 by bolting them to the columns or other members 21, 21 or 25 by loosely attaching the same by the recessed pockets, as shown in Figure 6, or by such other method as may be advisable.

These pipes 23, or such other horizontal supporting means as may be used, are arranged at 30 vertically-spaced intervals by inserting them in the holes or sockets provided for them in the brackets, thereby forming a series of horizontal supports.

35 A refractory-shape 24 is then placed in position on one such pipe 23, the recess 123 on the bottom of such block 24 engaging or accommodating the pipe 23 as is clearly indicated.

Thereupon a refractory-shape 25 is inserted from the rear, or it can be slipped in sidewise, 40 above the block 24 and its boss 27, at the rear and top of the element 25, engages the back of the next upper support 23, and is held in place thereby.

When these two shapes 24 and 25 are in position, they are maintained in that relation by the friction of their intermediate contacting surfaces 28 and 29, and, as the indicated operation is continued, it will be readily seen that each group of two or more shapes suspended or held 50 in place in this manner will be self-supporting with relation to the adjoining group or groups and provision can be made for the expansion of the same without imposing strain on the adjacent construction.

55 If preferred, shapes or tiles 24 and 25 can be grooved or recessed at the joint between them at 30, 30 and, when these indentations are filled with clay or a plastic material, one or a series of sealing joints will be provided to prevent the 60 leakage of air or gas between such shapes, and such filling of these grooves will also afford greater frictional resistance between the shapes for maintaining the same in their proper relation.

For the purpose of preserving the alignment of 65 the tiles or shapes at such times as the refractory material is not of the proper texture or nature to supply the necessary frictional resistance between the shapes, it is intended, if necessary, to use an anchor or section of burned fire-clay or other material 31, of the proper size and shape to fit registering recesses or indentations 70 130 in the adjacent surfaces of the shapes, such material 31 being inserted as the wall is erected or placed between the shapes from the side after 75 such shapes or tiles are in place.

The tiles located at the supporting-brackets may be recessed, as shown in Figures 1 and 2, or otherwise, to fit around such brackets and permit the introduction of the tiles from the back with sliding along thereafter sidewise into place 5 meeting the remaining tiles.

By this means the shapes will be held in proper correlation of alignment or register and also, in case of the breakage of the shapes during the operation of the furnace, these members will 10 serve to prevent portions or sections of the shapes from falling away.

Provision may be made for sealing the expansion joints at 26 by extending the vertical portions of the tiles 25 immediately in front of the 15 supporting members 23 downwardly at 127 and providing a registering vertical surface 124 (Fig. 7) on the tiles 24, thus supplying an offset horizontal joint definitely sealed by the use of fire-clay, plastic or other character of seal. 20

Each tile may be recessed on one side vertically at 100 to receive a rib 101 on the next adjacent tile, thus effecting a tight vertical joint between adjacent tiles or shapes.

In assembling the members forming the wall, 25 the tiles may be placed so that they register one above the other, or preferably staggered, as shown in Figure 1, in order to simplify the erection of the same, so that when a lower tile is put in position, it is held and supported in its proper 30 place until the upper tile 25 is slipped into position, as the two tiles form an independently-supported unit, and by staggering the tiles, i. e., by arranging the upper tiles so that the joints of the same register at some intermediate points of 35 the lower tiles, the latter are held in place by the overlapping tiles as the erection work progresses.

The same general arrangement, as depicted in Figure 1, can be employed with a greater number 40 of tiles between each pair of supporting pipes or tubes, the construction being the same as shown in such Figure 1 except that three such tiles 31, 38 and 39 are employed (see Fig. 4), the tiles 37 and 39 being substantially like those 45 24 and 25 of Figure 1, the intermediate tile 38 being of a somewhat different conformation, as is clearly shown, and, in this case, the anchors 131 are rectangular in cross-section instead of round and the tile recesses 132 are correspondingly shaped.

In the illustrations, provision is made for the insulation of the wall, if desired, by the use of block or plastic insulating materials such as that designated 33 in Figures 2, 3, 4 and 5, in which 50 case the temperature of the supporting-members embedded in the wall will be materially increased, so that the use of alloy or heat-resisting castings or supporting-members 22 or 122 and 23, may be necessary, and it will be noted 60 from these drawings that the only connection between the hot portion of the wall and the outside of the same is a small section of the brackets 22 or 122, thus reducing the heat transmission to the outer surface to a minimum. 6

It is necessary, or desirable, in a construction of this type that it be a suspended wall to prevent cumulative loading of the refractories or insulating-material and, at the same time, permit of a material reduction in the weight of the furnace enclosure at these points. 7

As a modification or alteration of the structures already described, an individual group or panel construction will now be considered as it is probable that, at times, this character or ar- 7

angement may be desirable, for example, a series of individual groups or panels may be bolted or otherwise assembled in place and when thus in position, comprise a complete unit.

5 A group or panel, Figs. 13-18, consists of a frame composed of a base angle-bar 41, end upright angle-bars 42, 42, and a top cross-strip 43 secured together in any approved manner and having the brackets or clips 22, 22 bolted or 10 otherwise attached thereto in proper position, these brackets, as in the previous instance, being apertured and supporting the pipes or rods 23, 23.

15 The tiles are carried individually or in groups by the pipes 23 and when the tiles are in place, they comprise a self-supporting unit.

When assembling the parts of the wall, the brackets 22, 22 are attached to the frame or supporting members 42, 42 at intervals spaced for 20 the proper support of the refractory shapes to be employed therewith.

25 A row or series of shapes 44 is placed on the projecting ledge 41 and pipe 23 is then inserted in the corresponding brackets 22, 22 which will hold the tiles 44 in a horizontal position.

30 The next row or series of tiles 45 are then placed in position and above them the next row or series of shapes 44 are inserted and the corresponding pipe or supporting member 23 is introduced engaging the recesses in the tiles and, 35 when in place, holding the group of tiles 44 and 45 in position, the tension or friction of the surfaces between the tiles 44 and 45 at the point 40 serving to hold the refractories in tension and in a horizontal position.

35 The indicated operation is continued until the top of the group or panel is reached and this is completed by a row or series of shapes 45 which engage the pipe 23 at the recesses at the bottom of the shapes.

40 From this it will be seen that each group or panel consists of a series of refractory shapes which are in turn carried individually or in pairs in such a manner that the refractory shapes are not subject to cumulative loading and a series 45 of panels may be assembled to meet the requirements of the installation, as by bolting their upright flanges together as shown in Figure 15.

45 Another embodiment of the invention is portrayed in Figure 19, and, in this instance, each panel comprises a supporting sheet-metal plate 51 with integral, stiffening and reenforcing, marginal, vertical flanges 52, 52, each such plate being bolted or otherwise secured at its middle portion at 53, 53 to one of the upright columns 21.

50 The angle-brackets 22 are fastened to the face of such panel-sheet and these brackets accommodate in their aligned apertures the tile-supporting members, such as the pipes 23, 23.

55 These panels are joined together at their ends by reason of the apertured flanges similar to the manner indicated in Figure 15 in connection with the other embodiment of the invention.

60 A particular advantage of this invention is its extreme simplicity in design and erection, the use of standard shape refractories with slight changes instead of a number of special shapes involving mold cost and expensive manufacture, its adaptability to various structural 65 and operating conditions with minor modifications in detail together with the simplest form of supporting members and an extremely low heat leak or radiation loss.

65 Those acquainted with this art will readily understand that the invention, as defined by the

appended claims, is not necessarily limited and restricted to the precise and exact details of structure shown and described and that various modifications and changes may be resorted to without departure from the heart and essence 5 of the invention and without the loss or sacrifice of any of its material benefits and advantages.

I claim:

1. In a furnace-wall structure, the combination of columns, brackets mounted on said columns in vertically-spaced relation and in horizontal alignments, horizontal supporting-members carried by said brackets, and groups of superposed refractory-blocks mounted between 10 pairs of said supporting-members, the lowermost block or blocks of each group resting on one of said supporting-members and each having a channel in its under surface receiving said member, the uppermost block or blocks of each 15 group each having a projection located behind and in engagement with the next higher supporting-member, the blocks of each group of the same level resting on, and in frictional-engagement with, those of the same group of the next 20 lower level.

2. In a furnace-wall structure, the combination of columns, recessed brackets mounted on said columns in vertically-spaced relation and in horizontal alignments, horizontal supporting 30 pipes carried by said brackets and occupying the recesses thereof, and groups of superposed refractory blocks mounted between pairs of said pipes, the lowermost block or blocks of each group resting on one of said pipes and each having a channel in its under surface receiving said pipe, the uppermost block or blocks of each 35 group having a projection located behind, and in engagement with, the next higher pipe, the blocks of each group of the same level resting on, and in frictional-engagement with, those of the same group of the next 40 lower level.

3. In a furnace-wall structure, the combination of columns, socket-members secured to said columns in vertically-spaced relation and in 45 horizontal alignments, brackets seated in said socket-members, horizontal supporting-members carried by said brackets, and groups of superposed refractory-blocks mounted between 50 pairs of said supporting-members, the lowermost block or blocks of each group resting on one of said supporting-members and each having a channel in its under surface receiving said member, the uppermost block or blocks of each 55 group each having a projection located behind, and in engagement with, the next higher supporting-member, the blocks of each group of the same level resting on, and in frictional-engagement with, those of the same group of the next 60 lower level.

4. In a furnace-wall structure, the combination of columns, double-ended brackets mounted on said columns in vertically-spaced relation and in horizontal alignments, each end of each such bracket being apertured, horizontal supporting-members carried by said brackets and occupying said apertures, and groups of superposed refractory-blocks mounted between pairs of said supporting-members, the lowermost block or blocks of each group resting on one of 70 said supporting-members and each having a channel in its under surface receiving said member, the uppermost block or blocks of each group having a projection located behind, and in engagement with, the next higher supporting- 75

member, the blocks of each group of the same level resting on, and in frictional-engagement with, those of the same group of the next lower level.

5. In a furnace-wall structure, the combination of columns, brackets mounted on said columns in vertically-spaced relation and in horizontal alignments, horizontal supporting-members carried by said brackets, groups of superposed refractory-blocks mounted between pairs of said supporting-members, the lowermost block or blocks of each group resting on one of said supporting-members and each having a channel in its under surface receiving said member, the uppermost block or blocks of each group each having a projection located behind, and in engagement with, the next higher supporting-member, the blocks of each group of the same level resting on, and in frictional-engagement with, those of the same group of the next lower level, and locking-keys occupying registered grooves in the top and bottom contacting faces of the blocks of said groups.

6. In a furnace-wall structure, the combination of columns, brackets mounted on said columns in vertically-spaced relation and in horizontal alignments, horizontal supporting-members carried by said brackets, groups of superposed refractory-blocks mounted between pairs of said supporting-members, the lowermost block or blocks of each group resting on one of said supporting-members and each having a channel in its under surface receiving said member, the uppermost block or blocks of each group each having a projection located behind, and in engagement with, the next higher supporting-member, the blocks of each group of the same level resting on, and in frictional-engagement with, those of the same group of the next lower level, and locking-keys angular in cross-section occupying registering grooves angular in cross-section in the top and bottom contacting faces of the blocks of said groups.

7. In a furnace-wall structure, the combination of columns, brackets mounted on said columns in vertically-spaced relation and in horizontal alignments, horizontal supporting-members carried by said brackets, and groups of superposed refractory-blocks mounted between pairs of said supporting-members, the lowermost block or blocks of each group resting on one of said supporting-members and each having a channel in its under surface receiving said member, the uppermost block or blocks of each group each having a projection located behind, and in engagement with, the next higher supporting-member, the blocks of each group of the same level resting on, and in frictional-engagement with, those of the same group of the next lower

level, each said blocks having a rib on one vertical side occupying a complementary groove on the adjacent vertical side of the next block.

8. In a furnace-wall structure, the combination of columns, metallic-panels secured to said columns, brackets mounted on said panels in vertically-spaced relation and in horizontal alignments, horizontal supporting-members carried by said brackets, and groups of superposed refractory-blocks mounted between pairs of said supporting-members, the lowermost block or blocks of each group resting on one of said supporting-members and each having a channel in its under surface receiving said member, the uppermost block or blocks of each group each having a projection located behind, and in engagement with, the next higher supporting-member, the blocks of each group of the same level resting on, and in frictional-engagement with, those of the same group of the next lower level.

9. In a furnace-wall structure, the combination of columns, metallic-panels secured to said columns, brackets fastened to each of said panels in vertically-spaced relation and in horizontal alignments, horizontal supporting-members carried by said brackets, groups of superposed refractory-blocks mounted between pairs of said supporting-members, the lowermost block or blocks of each group resting on one of said supporting-members and each having a channel in its under surface receiving said member, the uppermost block or blocks of each group each having a projection located behind and in engagement with the next higher supporting-member, the blocks of each group of the same level resting on, and in frictional-engagement with, those of the same group of the next lower level, a ledge at the bottom of each of said panels, and a row of base blocks mounted on each said ledge.

10. In a furnace-wall structure, the combination of columns, metallic-panels secured to said columns and having marginal flanges along adjacent edges, means fastening said flanges together, brackets mounted on said panels in vertically spaced relation and in horizontal alignments, horizontal supporting-members carried by said brackets, and groups of superposed refractory-blocks mounted between pairs of said supporting-members, the lowermost block or blocks of each group resting on one of said supporting members, and each having a channel in its under surface receiving said member, the uppermost block or blocks of each group each having projection located behind, and in engagement with, the next higher supporting-member, the blocks of each group of the same level resting on, and in frictional-engagement with, those of the same group of the next lower level.

FRANK BURR BIGELOW.
